United States Patent Office

Des. 186,544
Patented Nov. 3, 1959

186,544

STOCKING

Lawrence S. Smith, New York, N.Y.

Application January 10, 1958, Serial No. 49,194

Term of patent 14 years

(Cl. D47—7)

Figure 1 is a side elevational view of a stocking embodying my design.

Figure 2 is a rear elevational view of the stocking shown in Figure 1.

Figure 3 is a cross-sectional view taken on lines 3—3 of Figure 2.

I claim:

The ornamental design for a stocking, as shown.
